UNITED STATES PATENT OFFICE.

GROVER M. REPP, OF NEW YORK, N. Y., ASSIGNOR OF ONE-HALF TO MAURICE J. O'CONNOR, OF BROOKLYN, NEW YORK.

TYPOGRAPHIC FORM.

Application filed March 23, 1923. Serial No. 627,064.

To all whom it may concern:

Be it known that I, GROVER M. REPP, a citizen of the United States, and a resident of the borough of Manhattan, city, county, 5 and State of New York, have invented certain new and useful Improvements in Typographic Forms, of which the following is a specification.

This invention relates to a device for non-10 adjustably positioning printing plates on a collective form base.

When a number of printing plates, such as electrotypes, are imposed on a base in collective form, a careful adjustment of the 15 face of each individual plate of each and several forms of a specified job to be printed is required to bring each plate into its proper position on the base relative to the face of the other plates. This requires the 20 printing of several trial sheets from each form of adjustably imposed plates and the readjustment of the plates of each and the several forms until they are accurately positioned.

25 An object of the present invention is to provide a device by which ordinary adjustable printing plates may be accurately and non-adjustably imposed in proper position on the first form or on the several 30 following forms without the necessity of trial sheets or manual adjustment of plates either on the first form or on the following forms.

Another object of the invention is to provide 35 printing plates and a collective form base each having co-operating means for non-adjustably positioning said plates on said base and holding them from movement horizontally.

40 Another object of the invention is to provide non-adjustable positioning means in the base and the adjacent bottom surface of the printing plate by which the plates are collectively spaced and aligned in two directions.

45 Another object of the invention is to provide as holding means grooves so situated in the bottom of the plate as to be aligned with the printing face of the plate.

50 A further object of the invention is to provide co-operating means of grooves in the plates which so co-operate with grooves in the collective form base as to obtain an accurate alignment of the printing face ir-

respective of the faulty or irregular flange 55 edges of the plate.

With these and other objects in view the invention comprises the device described and set forth in the following specifications and claims. 60

The various features of the invention are illustrated in the accompanying drawings in which:

Fig. 1 is a plan view of a base and an assembled group of printing plates mounted thereon illustrating an embodiment of 65 my invention.

Fig. 2 is a section on line 2—2 of Fig. 1.

Fig. 3 is a perspective view of the collective form base with one plate in place 70 and the splines shown in position.

Fig. 4 is a view of the bottom surface of a plate such as shown in Figs. 1 and 3.

Fig. 5 is a perspective view of the splines.

Fig. 6 is a perspective view of another 75 form of spline shaped as a cross suitable for use with any of the bases.

Fig. 7 is a plan view of a base and an assembled group of printing plates illustrating another embodiment of my invention. 80

Fig. 8 is a view in perspective of the collective form base with one plate in position.

Fig. 9 is a section on line 9—9 of Fig. 7.

Fig. 10 is a view of the bottom surface 85 of a plate such as shown in Figs. 7 and 9.

Fig. 11 is an assembly of splines suitable for use with the structure shown in Figs. 7 and 10.

In the present invention the base on which the plates are imposed is provided with 90 positioning means extending in intersecting or co-ordinating directions and the printing plates are provided with corresponding 95 positioning means so positioned that when they are imposed on the non-adjustable positioning means in the base, or in their co-operating relation to the means of the base, the printing faces are in their exact spaced 100 and aligned position. The positioning means in the base is preferably formed of a system of grooves part of which are parallel to each other and at right angles to other parallel grooves. The printing plates are provided on their bottom surfaces with 105 co-operating grooves, also arranged at right angles and adapted to be positioned in the plates so that when superposed on the

grooves of the base the plates are in their correctly spaced and aligned positions. Separate splines or keys are positioned in the grooves of the base and project into the grooves of the printing plates in such manner that when the plates are properly positioned to bring the grooves of the plates and base into superposed position the splines will engage and hold the plates in their proper and non-adjustably aligned position.

Referring more particularly to the accompanying drawing, a base 10 is provided with grooves 12 extending in a longitudinal direction and grooves 14 intersecting the grooves 12 at right angles as shown in Figs. 1 to 3 or with cross shaped grooves 15 as shown in Figs. 7 to 9. The parallel grooves 12 and 14 or the cross shaped groove 15 are non-adjustably spaced in accordance with the collective form to be printed and the size and spacing of the plates to be mounted on the collective form base.

Splines 16 and 18 are mounted in the grooves 12 and 14 respectively and extend above the face of the base, as indicated in Fig. 3, to project into and engage suitable grooves on the bottom surface of the plates which are to be imposed on the base. Instead of splines adapted to be mounted individually and separately in the grooves 12 and 14 or in groove 15, single compound splines in the form of a cross 20, as illustrated in Fig. 6 in the form of T's or L's 22, as illustrated in Fig. 11, may be employed to be mounted in the intersections of the said grooves.

Printing plates 24 to be imposed on the collective form base 10 are provided in their bases with grooves 26 and 28 situated at right angles to each other or with cross shaped grooves 29 (Fig. 10) to receive the projecting portions of the splines 16 and 18, or 20, or 22. The grooves 26, 28 or 29 are so positioned with the plate printing edges 24^a, 24^b, 24^c and 24^d that when they receive the splines which project above the base they are in their correct spaced and aligned position relative to the printing face 24 of each other in collective form for printing. Thus, in the example illustrated in the accompanying drawing, the printing faces of the plates 24 (which faces are bound respectively by 24^a, 24^b, 24^c and 24^d) are arranged in two rows with the adjacent edges of the printing faces of the plates parallel to each other, and the other edges of the printing faces in alignment with each other irrespective of whether the flanges 30 and 36 which extend from the printing edges of the plates are crooked and irregular or not. For this purpose the grooves 26 on each plate are parallel to the edges 24^a and 24^c of the printing faces and are spaced a sufficient distance there-

from to provide a correct distance between the edges 24^a of one printing edge and 24^c of the adjacent printing edge. Similarly, the grooves 28 of the plate are positioned at right angles to the grooves 26 and edges 24^a and 24^c of the printing faces thus providing the correct alignment and the corresponding grooves 14 in the base are spaced apart the width of the plates plus the distance between the printing faces to provide the proper spacing of the plates in the rows of plates.

Similarly, the respective cross shaped groove 15 in the base and 29 in the plate are so positioned as to give the correct spacing and alignment.

In assembling the plates on the base, which base may be a single piece of material or made up of a plurality of pieces of material fitted together, it is only necessary to place the splines in the grooves of the base and place the plates in position so that their grooves engage the splines to accurately position the printing face of the plates on the base. The plates may then be fastened to the base by means of tacks 34 driven into the flange edges 30 and 36 at the edge of the plates in the usual manner or may be fastened to the base in any other suitable manner.

Through this invention a rapid and accurate positioning and alignment of the printing face of the plates on the base is assured and the shifting of the plates on the base and testing of the accuracy of their adjustment with trial sheets are avoided.

The base, illustrated as one solid piece, can obviously be made up and composed of and from a plurality of individual base blocks, with each individual block grooved so as to co-operate with the non-adjustable means for positioning a collective form of printing plates.

As changes of construction could be made within the scope of my invention, it is intended that all matter contained in the above description or shown in the accompanying drawings be interpreted as illustrative and not in a limiting sense.

Having thus described my invention what I claim as new and desire to secure by Letters Patent is:

1. A device of the type described which comprises a form base having in collective formation grooves in its upper surface extending in intersecting directions to each other, splines in said grooves and plates having grooves in their bottom surface positioned non-adjustably to receive said splines.

2. A device of the type described which comprises a form base having in collective formation intersecting grooves in its upper surface, splines in said grooves, and a collective form of printing plates having

grooves positioned non-adjustably to receive the projecting portions of said splines.

3. A device of the type described which comprises a form base having in collective 5 formation grooves intersecting at right angles, splines in said grooves and projecting above the surface of said base, and a collective form of printing plates having grooves to receive the upwardly projecting 10 portions of said splines.

4. A device of the type described which comprises a form base having in collective formation grooves in its upper surface extending in intersecting directions, printing 15 plates imposed in collective form on said base and means extending from said plate into said grooves in said base.

5. A device of the type described which comprises a form base having in collective 20 formation splines projecting upwardly from its surface and extending along said surface in intersecting directions and a collective form of printing plates having grooves in their under surfaces to receive said splines.

25 6. A device of the type described which comprises a form base having in collective formation intersecting splines projecting upwardly from its surface and a collective form of printing plates on said base having 30 intersecting grooves to receive said splines.

7. A device of the type described which

comprises a form base having in collective formation splines projecting upwardly from the surface of the base and intersecting on 35 said surface at right angles and a collective form of printing plates on said base having grooves in their bottom surface to receive said splines.

8. A device of the type described which comprises a form base having in collective 40 formation parallel grooves extending longitudinally on its upper surface and parallel grooves in collective formation intersecting said grooves at right angles, printing plates non-adjustably imposed on said base having 45 grooves in their bottom surfaces intersecting at right angles and adapted to be superposed on the grooves of said base and splines adapted to lie in said opposing grooves to compose a collective form of printing plates. 50

9. A collective form base of the type described having grooves extending longitudinally in its upper surface and grooves in 55 said surface at right angles to said longitudinally extending grooves.

10. A collective form base of the type described having grooves extending longitudinally in its upper surface and grooves extending at right angles to said longitudinally extending grooves and splines mounted in said intersecting grooves. 60
